Primary Examiner — Stella M Reid*Assistant Examiner* — Elizabeth J Oswecki(74) *Attorney, Agent, or Firm* — Ohlant, Greeley, Ruggiero & Perle, L.P.(57) **CLAIM**

The ornamental design for a bottle, as shown and described.

DESCRIPTION

FIG. 1 is a first, perspective view of a bottle showing our new design; and,

FIG. 2 is a second, perspective view thereof.

The broken lines in the drawings are for the purpose of illustrating environmental structure or boundaries only and form no part of the claimed design.
